(57) **CLAIM**

We claim the ornamental design for a substrate transfer structure, substantially as shown and described.

DESCRIPTION

FIG. 1 is a top view of a substrate transfer structure showing our new design;

FIG. 2 is a top angled view of the substrate transfer structure; FIG. 3 is a perspective view of the substrate transfer structure;

FIG. 4 is a left side view of the substrate transfer structure, with the right side and back side views being identical images thereof; and,

FIG. 5 is a front side view of the substrate transfer structure. The broken lines are for the purpose of showing environmental structure, and form no part of the claimed design.
